SPLIT CORE PROBE FOR AN A.C. VOLTMETER-AMMETER

Samuel J. Koch, Great Neck, N.Y., assignor to SOSS
Manufacturing Company, Detroit, Mich., a corporation
of Maine

Filed Dec. 29, 1964, Ser. No. 83,203

Term of patent 14 years

(Cl. D26—1)

FIG. 1 is a left side, bottom and front perspective view of a split core probe for an A.C. voltmeter-ammeter, showing my new design in closed position;

FIG. 2 is a left side, bottom and front perspective view of the probe in open position;

FIG. 3 is a front elevational view of the probe in closed position;

FIG. 4 is a right side elevational view of the probe in closed position;

FIG. 5 is a rear elevational view of the probe in closed position;

FIG. 6 is a left side elevational view of the probe in open position;

FIG. 7 is a front elevational view of the probe in open position;

FIG. 8 is a top plan view of the probe in closed position;

FIG. 9 is a top plan view of the probe in open position;

FIG. 10 is a bottom plan view of the probe;

FIG. 11 is an end elevational view of the connecting

plug, the opposite end being substantially a mirror image thereof; and

FIG. 12 is a side elevational view of the plug, the opposite side being substantially a mirror image thereof.

A portion of the connecting wire has been omitted from FIGS. 1 and 2, the plug and connecting wire have been omitted from FIGS. 3 to 10, inclusive, and the probe and connecting wire have been omitted from FIGS. 11 and 12 for convenience in illustration.

I claim:

The ornamental design for a split core probe for an A.C. voltmeter-ammeter, substantially as shown and described.
